UNITED STATES PATENT OFFICE

VICTOR LAGNEAU, OF TAININES, BELGIUM

STOVE

Application filed August 25, 1931, Serial No. 559,299, and in Belgium September 2, 1930.

This invention relates to stoves and like heating apparatuses burning solid fuel, having a fuel hopper or container fitted above the hearth.

5 In some devices of this kind, the gases generated by heat in the fuel are returned by a downpipe from the top of the hopper to the hearth or to the exit from the same, in order to be consumed. If the fuel is tightly 10 compressed or if it contains much dust, the passage of the gases generated in the lower portion of the fuel column, through the upper layers and towards the collector is greatly impeded, and the quantity of gas recovered through the latter is frequently very 15 slight.

According to my invention, this disadvantage is overcome by collecting the gases from the reserve of fuel, at the spot where they 20 are generated, through one or more openings provided at one or more levels intermediate the height of the container, by mixing said gases with air and leading them to a point adjacent the glowing fuel, where they ignite. 25 The collector thus provided with gas-collecting openings, of a number variable according to requirements, may be of any appropriate shape and be located beside the mass of fuel or within the same, inside or outside the 30 stove. It consists preferably of a semi-tubular member of metal or refractory material, closed at its upper end and detachably secured to the rear wall of the stove.

Air may be admitted through the fuel 35 container but is preferably allowed to enter the gas-collecting duct directly, through one or more openings provided in the adjacent wall of the stove. Said openings may be regulated by means of automatic or adjustable 40 valves or dampers.

The bottom portion of the gas collector opens at the level of the exit from the hearth, the latter being conveniently closed by means 45 of an upright grate, adapted to retain the incandescent fuel within the hearth, said grate being detachable and being likewise adapted to support the gas collector.

In the accompanying drawings:

Fig. 1 is a vertical section of one constructional embodiment of the invention,

Figs. 2 and 3 are cross-sections on lines A—B and C—D of Fig. 1 respectively,

Fig. 4 is a vertical section of another constructional embodiment of the invention,

Fig. 5 is a fragmental section of the same, on line E—F of Fig. 4,

Fig. 6 shows to an enlarged scale the gas collector of Fig. 4, as viewed from inside the stove,

Fig. 7 is a section on line G—H of Fig. 6,

Fig. 8 is a vertical section of the upper portion of a gas-collector, having an air valve controlled by the handle regulating the draught in the chimney.

Fig. 9 is a frontal view of the air admission valve shown in Fig. 8, and

Figs. 10 and 11 respectively, are a frontal view and a vertical section view of an auxiliary air inlet.

With particular reference to Figs. 1 to 3, 1 is the gas collector consisting of a semi-tubular member removably fitted against the rear wall 2 of the fuel container or hopper 3 and adapted to collect and to deliver to the outlet 4 of hearth 5 the gases generated within the fuel contained in the hopper. Said gas collector 1, the lower portion of which is open, is closed at its upper end by a partition 6 which prevents the fuel entering it. It is provided with vertical slits 7, 8, 9, 10, through which escape the gases released by the heating of the mass of fuel 11, said slits being situated at various heights and gathering said gases at the levels at which they are generated. The gases are drawn by the draught towards the outlet of gas-collector 1, where they ignite. The slits 7, 8, 9 and 10 may increase or decrease in size from bottom to top of the collector, according to requirements.

Apart from the gas-collector 1, the stove illustrated in Figs. 1 to 3 may be provided with a draught flue 12, having one end adjacent the upper end of hopper 3, behind gas-collector 1, and the other end adjacent the exit 4 of hearth 5, and in proximity to a heat regenerator 13, adapted to gather the consumed gases at the level of said exit and convey them to the chimney at 14. Three valves or dampers 15, 16, 17 are provided to

regulate the flow of the gases through the exit 4 of the hearth, the draught flue 12 and the chimney 14 respectively, combustion air being conveniently admitted within the lower portion of the stove by means of a screw valve 18 and within the upper portion of the same by means of an automatic flap valve 19.

The foregoing arrangement allows very fast, average, or slow combustion to be secured as desired. In the first case, all valves and air inlets are open and the gases generated within the reserve of fuel 11 are drawn through the slits of gas-collector 1, to be consumed at the bottom of the same together with the gases drawn from the upper portion of the container by the draught flue 12, the whole of the consumed gases then passing into the heat regenerator 13, where they give up their heat. In the second case, the valve 16 of draught flue 12 is closed, whilst valve 15 of the hearth and the air inlet screw-valve 18 are partly closed. In the third case said valves are further closed and the gas-collector 1 continues to draw off the gases generated within the reserve fuel 11. Combustion may be further regulated, if desired, by means of chimney damper 17.

In the constructional embodiment shown in Figs. 4-7, a port 20, provided in wall 2 of the stove connects the interior of gas-collector 1 directly with the outside air and is adapted to admit within said collector the air needed for the combustion of the gases generated by the reserve fuel 11 and drawn into said collector through slits 7, 8. Said port may be at the top of the gas-collector, as shown, or may face slits 7, 8, or it may be placed at a lower level, according to the suctional effect which the gas collector is required to exert upon the gases. The port 20 is provided with a valve constructed as shown in Figs. 4-7, consisting of a flap 21 adapted automatically to open more or less widely, according to the vacuum set up within the gas-collector 1 by the draught of chimney 14, towards which chimney the consumed gases flow through the heat regenerator 13. The draught may be regulated by means of chimney draught damper 22.

In the alternative constructional embodiment illustrated by Figs. 8 and 9, the valve 23 of port 20 is not automatic but is controlled, either independently or in conjunction with the chimney draught damper 22, and consists of an arcuate plate 23 slidably fitted in a curved raceway 24, secured to wall 2 of the stove. A handle 25, pivotally mounted at 26 upon heat regenerator 13, allows said valve 23 and the chimney draught damper 22 to be controlled simultaneously by means, on the one hand, of a forked arm 27 engaging a stud 28 of the valve 23 and, on the other hand, of a crank 29 integral with the axis of damper 22 and fitting within a fork 25' of said handle 25. By means of this

dual control it is possible at all times exactly to secure the required correlation between the quantity of air admitted within the gas-collector 1 and the strength of the draught or, in other words, to secure the desired rate of combustion in the stove.

It is desirable, in the case of the automatic flap valve as well as in that of the adjustable damper, that the upper part of collector 1 be hermetically sealed towards the container 3, by luting its edges with a suitable cement, for example, in order that port 20, opening into said upper part, should admit no gas therein but only air. This being done, if the draught be reduced and the gases are not drawn actively downwards, the air cushion thus formed prevents said gases from rising to port 20 and, in the case of a backflow, air alone is driven through said port, the gases being prevented from escaping into the room to be warmed.

Upon the stove being filled and lit, the distillation gases of the fresh fuel 11 are drained through said fuel towards slits 7, 8 of collector 1, are mixed within the latter with the air entering through port 20 and are ignited whilst flowing through exit 4 into the regenerator 13. Owing to their being drained through the fuel, the gases cannot accumulate in the upper portion of the container 3 whilst, on the other hand, the direct entry of air into collector 1 ensures complete combustion of the gases collected by the same.

An upright grate 30, fitted within the exit 4 of the hearth 5, prevents the fuel from dropping from said hearth into the heat regenerator. Said grate 30, mounted in exit 4 from without, is prevented by its chamfered edges (Fig. 5), from falling forwards into the hearth while two claws 31 provided at its lower part and two lugs 32, integral with semi-tubular collector 1, keep it from falling backwards. Lugs 32 extend through two slots 33, in the edge of exit 4, engage in two notches 34, in the upper crossbar of the grate, and hook into said grate from behind.

The semi-tubular collector 1 rests upon said cross-bar of grate 30 through its lugs 32. Its upper portion is likewise secured by two tenons 35, fitting within holes 36 of a ring 37 forming an annular seating for the lid of the stove. When said ring is in position, semi-tubular collector 1 thus is held against wall 2 of the stove whilst itself holding grate 30 in its place.

To disassemble the parts, the ring 37 is raised, collector 1 is pivoted inwardly of the stove round its lugs 32, to withdraw the latter from the slots 33 by freeing them from the notches 34 of grate 30, and thereupon said grate may be removed from outlet 4 by drawing it backwards and turning it through 90°, to enable its passing through outlet 4. An inspection orifice, consisting of a door 38 at the bottom of heat regenerator 13, gives ac-

cess to the grate 23 from the rear and facilitates manipulation.

An auxiliary air inlet 39 may be provided in door 38 (Figs. 10, 11) or other suitable portion of heat regenerator 13, the valve 40 of said air inlet 39 being controlled by a shutter 41 and being opened, when reduced draught is required. Auxiliary inlet 39 ends, within the heat regenerator 13, in a cavity of which the lower part alone is open. Said cavity 42 is always filled by an air cushion which, as is the case with that filling the upper portion of semi-tubular collector 1, acts as a pneumatic seal to prevent the propagation of gas through inlet 39.

Although the constructional embodiments herein described and illustrated by way of example are highly satisfactory, the invention is not limited to the same, except as defined by the appended claims. In especial, it is not necessary that the semi-tubular collector 1 should extend to the top of container 3, and the two or three superimposed tiers of slits or openings 7 and 8 might be replaced by one row only, or even by a single opening, suitably located and formed.

I claim:

1. In a stove, the combination of a fuel receptacle, the bottom portion of said receptacle forming a fire zone, a flue for leading off combustion gases from the bottom portion of said receptacle, a downwardly extending gas collector communicating with said receptacle at an intermediate point thereof, the bottom end of said collector opening in proximity to the inlet end of said flue, means for detachably securing said collector within said receptacle, and means for admitting air into said collector.

2. In a stove, the combination of a fuel receptacle; an air inlet and a gas outlet near the bottom of said receptacle, a tubular gas collector extending downwardly in said receptacle, an auxiliary air inlet opening into the top of said collector, the bottom end of said collector opening into said receptacle adjacent said gas outlet, lateral openings being provided in the wall of said collector to draw gases from the reserve of fuel in said receptacle, and means for removably securing said gas collector against a wall of said receptacle.

3. In a stove the combination of a fuel receptacle, an air inlet and a gas outlet at the side of said receptacle, a removable gas collector in said receptacle, said collector comprising a removable semi-tubular perforated shell fitting against a side wall of said receptacle, said shell being open at its lower end in proximity to said gas outlet, and means for detachably securing said shell to said side wall.

4. In a stove, the combination of a fuel receptacle, an air inlet and a gas outlet at the side of said receptacle, a grate across said

gas outlet, a removable gas collecting shell above said gas outlet, said shell having slits opening into said receptacle, the top end of said shell being closed and its bottom end being open, a cover for said receptacle, said cover being adapted to lock said shell in position against a wall of said receptacle.

5. In a stove, the combination of a fuel receptacle, an air inlet and a gas outlet near the bottom of said receptacle, a removable grate fitted in said gas outlet, a semi-tubular shell fitted against a side wall of said receptacle above said grate, said shell having slits opening into said receptacle, the bottom end of said shell being open, and means for detachably securing said shell to said side wall and to said grate.

6. In a stove, the combination of a fuel receptacle, an air inlet and a gas outlet near the bottom of said receptacle, a perforated member above said gas outlet, said member forming a gas collector with the adjacent wall of said receptacle, an air inlet at the top of said gas collector, a flap in said air inlet adapted to open under the action of a vacuum in said collector, said collector being open at the end adjacent said gas outlet.

7. In a stove, the combination of a fuel receptacle, an air inlet and a gas outlet near the bottom of said receptacle, an upward flue leading from said gas outlet, a downwardly extending gas collector in said receptacle communicating with the inside of said receptacle at an intermediate point of its height, the bottom end of said collector opening in proximity to said gas outlet, an auxiliary air inlet opening into said gas collector, and means for simultaneously controlling the flow of air through said auxiliary inlet and the draught in said flue.

8. In a stove, the combination of a fuel receptacle, an air inlet and a gas outlet near the bottom of said receptacle, an upward flue leading from said gas outlet, a gas collector extending downwardly in said receptacle, an auxiliary air inlet opening into the top of said collector, the bottom end of said collector opening into said receptacle near said gas outlet, lateral openings being provided in the wall of said collector to draw gases from the reserve of fuel in said receptacle, a chamber communicating through its lower end with the bottom portion of said flue, and an air inlet in said chamber.

VICTOR LAGNEAU.
